REEL CONSTRUCTION

Arthur A. Bureau, Chicago, Ill., assignor to Western Electric Company, Incorporated, New York, N. Y., a corporation of New York

Application July 16, 1937, Serial No. 153,893

8 Claims. (Cl. 242—77)

This invention relates to reel construction, and particularly to reels such as are used for transportation and storage of telephone cable, power transmission cable, wire, wire rope and the like.

5 Cable, wire, wire rope and the like are commonly wound upon comparatively large reels, which reels serve for storage purposes and means for transporting the materials. In many instances these reels are comparatively expensive to manufacture due to their size and construction requirements and it is necessary that they be returned to the manufacturer when the material wound thereon has been removed therefrom.

10 The object of this invention is to overcome these features in the storage and transportation of cable, wire, wire rope and the like and to provide a simple, durable, inexpensive reel for these purposes, which because of its cost would not necessarily require its return to the manufacturer.

15 A further object of the invention is to provide a reel of simple form which can readily be assembled without the use of special machines.

20 In attaining these objects the reel is constructed of two heads with a drum therebetween of different material. The reel drum is of cylindrical construction of sheet metal having lugs or projections that are turned at angles to its surfaces, which lugs or projections when assembled with the heads will bite into the inner surfaces of the heads of wood or the like, lodging themselves therein and resting over and upon the tieing bolts.

25 Other objects and advantages of the invention will be understood by reference to the following specification and drawing, in which

Fig. 1 is a side elevation of a reel embodying the invention;

30 Fig. 2 is a sectional view taken on line 2—2 of Fig. 1;

Fig. 3 is an enlarged sectional view showing the first steps in assembly of the heads with the drum;

35 Fig. 4 is an enlarged sectional view similar to Fig. 3 but showing the final assembly of the heads with the drum;

Fig. 5 is a sectional view taken on line 5—5 of Fig. 4, and

40 Fig. 6 is a perspective view of the sheet material prior to its cylindrical formation into the reel drum.

45 In the drawing a simple form of reel is shown by way of illustration. Referring to Figs. 1 and 2 the cylindrical drum is indicated at 10 and the heads 11 and 12. The heads 11 and 12 are pref-

erably of wood or the like and the drum 10 disposed therebetween of sheet material, such as metal. A series of tieing bolts 13 are adapted to secure or tie the heads together with the drum therebetween. The bolts as illustrated extend entirely through the heads and drum but the invention is not so limited as short bolts or other tieing means can be used which do not extend the entire width of the drum.

5 The drum 10 is preferably fabricated from a substantially rectangular sheet of material as shown in Fig. 6, having formed thereon either integral or secured thereto by any well known manner, such as welding, projections or lugs 14. These projections or lugs 14 as shown are at an angle to the plane of the sheet for a purpose hereinafter described and preferably taper toward a point as illustrated. Slots or apertures 15 are provided in these projections or lugs 14 extending to and terminating at one surface of the sheet material which in the completed drum will be the inner surface for the tieing bolts 13 and in the reel assembly these projections rest upon and pass over the bolts 13 as illustrated.

20 The sheet is rolled into cylindrical form and the ends secured together in any well known manner, such as by welding. In the drawing a reinforcing strip 16 is shown which is welded to the ends of the sheet to form a reinforced joint.

25 When assembling the illustrated reel the drum 10 which has been previously formed into cylindrical form is spaced between the heads 11 and 12 and the bolts 13 passed through the heads and drum with the lugs or projections resting upon the bolts at the termination of the slots or apertures 15 as shown in Fig. 4. The lugs or projections 14 resting upon the tie bolts 13 at the terminations of the slots or apertures 15, which slots or apertures terminate at the inner surface of the drum 10, will provide a line contact between the bolts 13 and the inner surface of the drum to reinforce the drum and aid in supporting the load upon the drum when in use, thus permitting

30 thinner sheet material from the drum construction than would otherwise be possible. The projections or lugs 14 being at angles to the inner and outer drum surfaces and the inner surfaces of the heads are forced into or below the surface of the heads of softer materials upon tightening nuts 17, as shown in Fig. 4, thus making a biting contact with the heads sufficient to lodge themselves into the inner surfaces of the heads, forming a

35 compact, durable and inexpensive reel construction.

40 While the invention is illustrated and described 45

50 55

more particularly with reference to reels for storage and transportation of cable, wire, wire rope and the like having wooden heads and a metal drum, the invention is not confined thereto but is intended to cover any other uses or modifications within the scope of the appended claims.

What is claimed is:

1. A reel comprising a pair of heads, a metal drum having a projection at each of its ends turned to form an obtuse angle with the inner surface of the drum, and means for securing the heads to the drum with the projection embedded in the inner surfaces of the heads.
- 10 2. A reel comprising a pair of heads, a metal drum having a series of integral projections at its ends turned inwardly to form obtuse angles with the inner surface of the drum, and means for securing the heads to the drum with the projections in biting contact with the inner surfaces of the heads.
- 15 3. A reel comprising a pair of wooden heads, a metal drum having inwardly turned apertured projections at each end thereof positioned between the heads, and a plurality of bolts contacting the inner surface of the metal drum extending through both heads and the apertures in the drum projections to secure the heads in biting contact with the projections.
- 20 4. A reel comprising a pair of heads, a drum having a series of slotted tapered projections at its end turned inwardly to form obtuse angles with the inner surface of the drum positioned between the heads, and a plurality of bolts extending through both heads and the slots in the drum projections to secure the tapered projections in biting contact with the heads.

5. A reel comprising a pair of head members, a drum of different composition than the head members having a series of pointed inwardly turned projections forming obtuse angles with the inner surface of the drum, and securing means passing through both heads and the projections securing the projections in biting contact with the inner surfaces of the heads.

6. A reel comprising a pair of wooden heads, a metal drum having a series of inwardly turned apertured projections at each end thereof positioned between the heads, and a plurality of bolts extending through both heads and the apertures in the drum projections to secure the heads to the drums in biting contact with said projections resting upon said bolts.

7. A reel comprising a pair of heads, a drum positioned between the heads, bolts securing the heads to the drum and projections on the ends of said drum contacting the inner surfaces of the heads and provided with apertures extending to the inner surface of the drum whereby line contact is made with the bolts by the inner surface of the drum and the termination of the apertures of the projections.

8. A reel comprising a pair of heads, a metal drum having a series of projections at its ends turned inwardly to form obtuse angles with the inner surface of the drum having slots terminating at the inner surface of the drum and bolts in contact with the terminals of the slots and the inner surface of the drum for securing the heads to the drum with the projections in biting contact with the inner surfaces of the heads.
